INVENTOR

UNITED STATES PATENT OFFICE.

HAROLD R. SAUER, OF RICHMOND HILL, NEW YORK, ASSIGNOR TO BIGELOW HART-FORD CARPET COMPANY, A CORPORATION OF MASSACHUSETTS.

DESIGN FOR A CARPET.

60,707.

Specification for Design.

Patented Mar. 21, 1922.

Application filed March 2, 1921. Serial No. 449,234. Term of patent 7 years.

To all whom it may concern:

Be it known that I, HAROLD R. SAUER, a citizen of the United States, residing at Richmond Hill, in the county of Queens and State of New York, have invented a new, original, and ornamental Design for a Carpet, of which the following is a specification, reference being had to the accompanying drawing, forming part thereof.

The drawing illustrates a portion of a carpet showing my new design.

I claim:

The ornamental design for a carpet, substantially as shown.

HAROLD R. SAUER.
